(57) **CLAIM**

The ornamental design for a training bench as shown and described.

DESCRIPTION

FIG. 1 is a perspective view of a training bench according to the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the training bench of FIGS.

1-8 showing an alternative configuration; and,

FIG. 10 is a perspective view of the training bench of FIGS.

1-8 showing an in-use position with motors.

The broken line showing of portions of the training bench and environmental structure is included for the purpose of illustrating subject matter that forms no part of the claimed design.

1 Claim, 7 Drawing Sheets
